DESIGN FOR AN ILLUMINABLE HOROLOGICAL INSTRUMENT OR SIMILAR ARTICLE

Royal Doolin, Newark, N. J.

Application April 23, 1947, Serial No. 138,554

Term of patent 14 years

(Cl. D42—7)

To all whom it may concern:

Be it known that I, Royal Doolin, a citizen of the United States, residing in the city of Newark, in the county of Essex and State of New Jersey, have invented a new, original, and ornamental Design for an Illuminable Horological Instrument or Similar Article, of which the following is a specification, reference being had to the accompanying drawing, forming a part thereof, in which:

Figure 1 is a front elevational view of an illuminable horological instrument showing my new design;

Figure 2 is a rear elevational view of the same; and

Figure 3 is a top plan view looking in the direction of the arrows 3—3 in Figure 2.

I claim:

The ornamental design for an illuminable horological instrument or similar article, as shown.

ROYAL DOOLIN.
